UNITED STATES PATENT OFFICE.

WILLIAM H. PAGE, OF NORWICH, CONNECTICUT, ASSIGNOR TO THE WM. H. PAGE BOILER COMPANY, OF SAME PLACE.

DOME FOR STEAM-BOILERS.

SPECIFICATION forming part of Letters Patent No. 536,041, dated March 19, 1895.

Application filed January 9, 1895. Serial No. 534,373. (No model.)

To all whom it may concern:

Be it known that I, WILLIAM H. PAGE, a citizen of the United States, residing at Norwich, in the county of New London and State of Connecticut, have invented certain new and useful Improvements in Domes for Steam-Boilers; and I do hereby declare the following to be a full, clear, and exact description of the invention, such as will enable others skilled in the art to which it appertains to make and use the same.

My invention relates to steam and hot water boilers of that class technically known to the art as sectional boilers, in which the structure is "built up" of a number of cast metal sections to produce the fire pot, the water containing sections and a dome section, which sections are superposed one upon the other and suitably united together.

The special feature of the improvement contemplated by this invention relates to the top section or the steam dome section, cast in a single piece of metal, and comprising upper and lower walls substantially parallel to each other, an annular surrounding wall which joins the edges of said horizontal walls and forms a chamber therewith, a central water opening or nipple in the lower horizontal wall, and vertical smoke flues arranged in circular series around said central opening or nipple and joined to the top and bottom walls through which said smoke flues open, whereby the products of combustion are carried by the smoke flues through the steam dome, and the water and steam from the other sections of the boiler are free to pass and circulate through the central opening or nipple in the lower wall of the section.

To enable others skilled in the art to which this invention relates to more readily understand my improvement, I have shown the preferred embodiment thereof in the accompanying drawings, forming a part of this specification, and in which—

Figure 1 is a vertical sectional elevation of one type of sectional boiler in which my improved steam dome section is used. Fig. 2 is a detail perspective view of the dome section detached. Fig. 3 is a sectional view of another type of sectional boiler with which my

dome section may be advantageously combined.

Like letters of reference denote corresponding parts in all the figures of the drawings.

A denotes my improved dome section which is cast in a single piece of metal. This section consists of the upper horizontal wall, *a*, the lower horizontal wall *b*, the annular vertical wall, *c*, a series of vertical smoke pipes *d*, and a central opening or nipple *e* in the lower wall *b*, within the circular series of smoke pipes *d*, and concentric therewith. The horizontal walls *a*, *b*, are substantially parallel to each other, and the annular inclosing wall *c* lies substantially at right angles to the walls *a*, *b*, although said annular wall *c* may be slightly inclined, as shown by Fig. 1, to give to the dome a tapered form in vertical section, whereby the diameter of the dome A at its upper part is somewhat in excess of the lower end of the dome. This annular vertical wall *c*, is joined to the edges of the top and bottom, *a*, *b*, and it forms therewith a chamber, *G*, in which is contained the hot water and steam of the boiler. The vertical smoke pipes *d* are arranged in circular series around, and concentric with, the central opening or nipple *e* in the lower wall *b* of the dome section, and said smoke pipes are integral with the walls *a*, *b*, of the section. The ends of the pipes *d* open through the top and bottom of the section, and they serve as smoke flues to carry the smoke and products of combustion through the steam and hot water chamber *G* of the dome section, thereby utilizing the heat to the best advantage. The opening *e* in the bottom of the section is preferably bounded by a flange *f* which depends below the wall *b* and produces the nipple, the latter affording a convenient means for the attachment of the water heating sections of the boiler to the top or dome section A.

In Fig. 1 of the drawings I have shown my improved dome section A combined with two water heating sections H and I, a fire pot section J, and a masonry inclosing wall K. The crown sheet of the fire pot is formed by the lower solid wall of the section I, and the section H has nipples at its top and bottom which are coupled, respectively, to the nipple *f* of

section A and to the nipple on the upper side of the section I. The section H has transverse smoke flues, *h*, formed in it, which flues *h* are in vertical alignment with the circular series of vertical smoke flues *d* of my improved steam dome. The wall of masonry K surrounds the sections of the boiler, and it is surmounted by a cast metal cap *k* which forms the smoke space, from which leads the exit pipe *k'*.

The dome section A has flanged openings, *g*, to which are coupled the circulating pipes *G'*, one of which is shown in Fig. 1.

In Fig. 3 of the drawings I have shown the dome section combined with portable sectional boilers. In the type of boilers shown by this figure, the smoke is compelled to circulate in or take a tortuous course through the boiler, and this is produced by combining with the dome A, the fire pot J, and the inclosing casing L, certain forms of water sections M, N, which are different in diameter and situated in alternate relation to one another. The larger sections *m* are provided with transverse smoke flues M which extend through them, and each section is of such diameter as to fit closely against the inclosing casing. The smaller sections N present practically continuous surfaces to the flame, heat, &c., and they are of less diameter than the sections *m*, so that the products of combustion are compelled to pass along the bottom sides of the sections N, up and around the edges thereof, and then pass toward the center of the boiler, and up through the smoke flues M in the next upper section, *m*, of the boiler.

In Fig. 3, I have shown the smaller heat de-

flecting section, N, next to the dome section, A, to cause the heat and products of combustion to pass around the edges of said section, N, and thence inwardly over the section N to the smoke flues in the steam dome. In Fig. 1, however, I have illustrated the deflecting and flue sections transposed, that is, the flue section is next to the steam dome, and the deflecting section is below the flue section. This arrangement of sections causes the products of combustion, after passing around the lower deflecting section, to circulate between the two sections, and thence pass through the smoke flues in both the flue section and the dome section, a part of the heat and products of combustion also passing around the dome section because there is a space provided between the dome section and the surrounding or inclosing walls of the furnace, as clearly shown.

Having thus fully described my invention, what I claim as new, and desire to secure by Letters Patent, is—

A dome section A, cast in a single piece, having the top and bottom walls *a*, *b*, joined at their edges by an annular wall, *c*, and forming the steam and water chamber, a central opening or nipple, *e*, in the bottom *b*, and a circular series of vertical smoke pipes *d* concentric with the opening or nipple *e*, the ends of said smoke pipes opening through the top and bottom, *a*, *b*, of said section, as set forth.

In testimony whereof I affix my signature in presence of two witnesses.

WILLIAM H. PAGE.
